US0D1035182S

(12) **United States Design Patent** (10) Patent No.: **US D1,035,182 S**
(45) Date of Patent: ** Jul. 9, 2024

(54) **AUTOMATIC CAT LITTER BOX**

(71) Applicant: **UBTECH ROBOTICS CORP LTD**,
Shenzhen (CN)

(72) Inventors: **Mingming Ji**, Shenzhen (CN); **Xinshui Huang**, Shenzhen (CN); **Kun Yang**, Shenzhen (CN)

(73) Assignee: **UBTECH ROBOTICS CORP LTD**,
Shenzhen (CN)

(**) Term: **15 Years**

(21) Appl. No.: **29/832,729**

(22) Filed: **Mar. 29, 2022**

(51) LOC (14) Cl. **30-11**

(52) U.S. Cl.

USPC **D30/161**

(57) **CLAIM**

The ornamental design for an automatic cat litter box, as shown and described.

DESCRIPTION

FIG. 1 is a first perspective view of an automatic cat litter box showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the article that form no part of the claimed design.

1 Claim, 8 Drawing Sheets
